United States Patent Office

Des. 185,826
Patented Aug. 4, 1959

185,826

DISPLAY HOLDER FOR PLATES OR THE LIKE

Albert Kizler, Houston, Tex.

Application December 13, 1957, Serial No. 48,897

Term of patent 14 years

(Cl. D80—9)

Fig. 1 is a front perspective view of a display holder for plates or the like showing my new design; and
Fig. 2 is a rear perspective view thereof;

I claim:

The ornamental design for a display holder for plates or the like, substantially as shown.
